[57] CLAIM

The ornamental design of a conference microphone, as shown and described.

DESCRIPTION

FIG. 1 is a front perspective view of a conference microphone showing my new design;
FIG. 2 is a front elevational view thereof;
FIG. 3 is a side elevational view thereof the side opposite being substantially a mirror image;
FIG. 4 is a top plan view thereof;
FIG. 5 is a bottom plan view thereof; and
FIG. 6 is a top perspective view of a modified embodiment of the design shown in FIGS. 1 through 5.
The broken lines in FIGS. 1 through 4 and 6 represent environment only and form no part of the claimed design.

FIG. 1

FIG. 2

FIG. 3

*FIG. 4**FIG. 5**FIG. 6*
